Attns.

UNITED STATES PATENT OFFICE.

ALVA E. WAGNER, OF DES MOINES, IOWA.

DOOR-LATCH.

1,227,709.

Specification of Letters Patent. Patented May 29, 1917.

Application filed November 11, 1915. Serial No. 60,960.

To all whom it may concern:

Be it known that I, ALVA E. WAGNER, a citizen of the United States, and resident of Des Moines, in the county of Polk and 5 State of Iowa, have invented a certain new and useful Door-Latch, of which the following is a specification.

The object of my invention is to provide a door latch of comparatively simple, durable and inexpensive construction, especially 10 adapted for garages, barn doors and the like.

Still a further object is to provide such a latch having parts so arranged that when 15 the door is swung open, the latch parts will automatically engage for locking and holding the door in its open position.

Still a further object is to provide such a door having parts so constructed that they 20 may be readily adjustable where such adjustment is necessary on account of the sagging of the door, or any peculiarities in the manner in which the door is hinged.

My invention consists in the construction, 25 arrangement and combination of the various parts of the device whereby the objects contemplated are attained, as hereinafter more fully set forth, pointed out in my claims and illustrated in the accompanying 30 drawings, in which:

Figure 1 shows a front elevation of a part of a building such as a garage having a door, the door and building being equipped with a latch device embodying my invention.

Fig. 2 shows an end elevation of the keeper.

Fig. 3 shows a horizontal sectional view of the door and building taken just above the latch, and

Fig. 4 shows a vertical sectional view 40 taken on the line 4-4 of Fig. 3.

In the accompanying drawings, I have used the reference numeral 10 to indicate generally a building having a door opening 45 around which is the frame 11.

Hinged to the frame 11 is a swinging door 12. Mounted on one of the upright members of the frame 11 at any desired height, is a plate 13 which is preferably mounted 50 over part of one of the hinges 14, as clearly shown in Figs. 1 and 3.

Bolts 15 are extended through the plate 13 near the corner thereof and are suitably mounted on the door frame 11. The plate 55 13 is provided with a plurality of screw-

threaded openings to receive screw-threaded bolts 16, preferably arranged in the form of a rectangle, as clearly shown in Fig. 4. The screw threaded bolts 16 are employed for the purpose of adjusting the plate 13 to 60 different angles and positions. It will be seen that by adjusting the nuts on the bolts 15, the plate 13 may be left spaced from the frame 11 and also from the hinge 14, or any other equivalent plate, and that by adjusting 65 the screwthreaded bolts 16 in various positions and then tightening the nuts on the bolts 15, the position of the plate 13 may be varied considerably. The screw-threaded portions of the bolts 15 extend through openings in the plate 13 which are of sufficient size to allow some play of the plates 13 on the bolts 15.

Mounted on the frame on the outer face of the plate 13 are a pair of upwardly and 70 outwardly extending horizontally spaced keeper members 17. The outer edge of the keeper member adjacent to the door 12 is beveled, as shown in Figs. 1 and 3, so as to cause the latch member 18, heretofore referred to, when it strikes the said keeper member 17 to slide upwardly.

Mounted on the door near the central portion therefrom from side to side is a bracket 19 in which is rotatably mounted a bolt 20, the end of which adjacent to the door 12 is screw-threaded to receive nuts 21. On the bolt 20, outside the bracket 19 is an annular collar 22 which may be integral with the bolt as desired. On the bolt 25 beyond the collar 22 is a horizontal bearing 23 in which is mounted a horizontal rod or shaft 24 which extends transversely across the door and has at its end adjacent to the hinged side of the door a member 18 arranged at right angles to the rod 24.

Mounted on the door 12 between the bracket 19 and the hinged side of the door is a bracket 25 having at its upper portion an upwardly projecting plate 26, in which 100 is formed a vertically elongated slot 27, in which is mounted the rod 24 and which limits the up and down movement of the said rod.

Formed on the bracket 25 is a flange 28 to which is pivoted a latch lever 29, having 105 a portion which extends away from the door below the rod 24, and a handle member 30 which extends through a suitable opening in the door to the interior of the building. It will be seen that on the outside of the 110

building, the rod can be manually operated, while from the inside its end adjacent to the hinged side of the door may be raised by adjusting the handle 30 downwardly.

5 In the practical operation of my improved door latch, after the latch has been installed on the door, it will be noted that when the door is closed, the parts extend in their relative positions shown in Fig. 1, with the 10 portion 18 spaced from the keeper members 11 in such position that when the door is swung toward open position, the member 18 strikes the door edge at the upper portion of the inner keeper 17 and is automatically 15 raised, and as the door moves to open position, the member 17 clears the upper portion of the keepers 17 and drops downwardly beyond them with the rod 24 received between the keepers 17, whereby the 20 door is locked in its open position. It will be obvious, of course, that the portions of the rod 24 together with the member 18 on the side of the bearing member 13 adjacent to the hinged side of the door is heavier 25 than the portion 24 on the other side of said bearing member, so that the member 18 normally tends to drop downwardly by gravity. Where double doors are used or where single doors are used, the door may be swung 30 open and will be automatically locked in its open position. When it is desired to close the door by a person approaching from the outside, the end of the rod 24 adjacent to the free or swinging side of the door may 35 be grasped, and lowered for thereby releasing the members 18 from the keepers and the door may then be swung to closed position. If it is desired to clear the door from the inside, the operator may lower the handle 40 30, thereby raising the member 18 until it clears the keeper, and the door can be pulled to closed position.

It is well known that doors are hinged at 45 slightly different angles, and that they tend to sag and it is my purpose to provide an adjustable plate with means for adjusting it to position to a sufficient extent to permit the parts to be placed on any door, so that the parts will be engaged at the proper time.

50 The advantages of a door latch such as that herein described, will be largely obvious from the foregoing description.

It will be understood that some changes 55 may be made in the construction and arrangement of the parts of my improved door latch without departing from its essential features and purposes, and it is my intent to cover by this application any such changes which may be included within the 60 scope of the following claims.

I claim as my invention.

1. A door latch, comprising a rod pivotally mounted between its ends to swing in a vertical plane, parallel with the vertical 65 plane of a door, means for limiting the

swinging movement of said rod, a transverse member on one end of said rod, a pair of keepers designed to be mounted on the frame of a building adjacent to the hinged edge of a door, and adjacent to said transverse member, one of said keepers having a beveled edge, the parts being so arranged that when the door is swung from closed to open position, said transverse member will strike said beveled edge and be moved upwardly to 70 position for clearing said last named keeper and will then drop behind said keepers with the said rod received between the keepers. 75

2. A door latch, comprising a rod pivotally mounted between its ends to swing in a 80 vertical plane parallel with the vertical plane of a door, a transverse horizontal member on said rod, a pair of keepers designed to be mounted on the frame of a building adjacent to the hinged edge of a 85 door, and adjacent to said transverse member, one of said keepers having a beveled edge, the parts being so arranged that when the door is swung from closed to open position, said transverse member will strike said beveled edge and be moved upwardly to position for clearing said keeper and will then drop behind said keepers with said rod received between the keepers, means for limiting the swinging movement of said rod, comprising a bracket designed to be mounted on 90 a door and having a vertically elongated slot for receiving said rod. 95

3. A door latch, comprising a rod pivotally mounted between its ends to swing in a 100 vertical plane, parallel with the vertical plane of a door, said rod being arranged with its heavier end on the side of its pivotal point adjacent to the hinged edge of the door, means for limiting the swinging movement of said rod, a transverse horizontal member on said rod, a pair of keepers designed to be mounted on the frame of a 105 building adjacent to the hinged side of a door, and adjacent to said transverse member, one of said keepers having a beveled edge, the parts being so arranged that when the door is swung from closed to open position, said transverse member will strike said beveled edge and be moved upwardly to position for clearing said keeper and will then drop behind said keepers with the said rod received between the keepers, said limiting means comprising a bracket designed to be mounted on a door and having a vertically 110 elongated slot for receiving said rod, and having a movable member extending below said rod and a portion designed to extend through a door. 115

4. A door latch, comprising a rod pivotally mounted between its ends to swing in a 120 vertical plane, parallel with the vertical plane of a door, means for limiting the swinging movement of said rod, a transverse horizontal member on said rod, a support 125

designed to be adjustably mounted on the frame of a building adjacent to the hinged edge of a door, and adjacent to the transverse member, a pair of keepers on said support, one of said keepers having a beveled edge, the parts being so arranged that when the door is swung from closed to open posi-

tion, said transverse member will strike said beveled keeper and be moved upwardly to position for clearing said keeper and will 10 then drop behind said keepers with the said rod received between the keepers.

Des Moines, Iowa.

ALVA E. WAGNER.
